Louis E. Peck, Pittsburgh, Pa., assignor to Thomas
Machine Manufacturing Company, Pittsburgh,
Pa., a corporation of Pennsylvania

Application October 27, 1937, Serial No. 171,223

3 Claims. (Cl. 164—23)

This invention relates to power presses for operating punches, dies and other tools and more particularly is concerned with improved means for supporting reciprocating parts, such as the tool slide of a power press.

Heretofore, it has been the standard practice in the construction of a power press of the character indicated to support the slide or tool holder of the press slidably in the gibs carried in the frame. The gibs are ordinarily in two pairs positioned on opposite or opposed sides of the slide and are usually made adjustable to compensate for wear. Because the means for reciprocating the slide, such as an eccentric and strap rod, are positioned immediately above the slide, the height of the gibs is limited so that in the continuous use of known presses it is necessary to continuously adjust the gibs for wear in order to preserve accurate tool movement. It has been proposed to position the gibs off-center with respect to the line of movement of the tool and the thrust of the eccentric so that the length or height of the gibs can be increased. This is said to reduce the wear between the gibs and the slide and the number of times that the gibs must be adjusted in service. However, it gives rise to the objection that the thrust of the eccentric is off-center with respect to the support of the slide by the gibs so that accurate tool alignment is difficult to maintain and wear and even chattering are likely to occur. In addition to the foregoing, lubrication of the wearing parts supporting the slide has presented difficulty inasmuch as the clearance between the crank shaft, eccentric, slide and other parts of the usual press does not permit the use of oil cups, and flexible tubing or other methods of lubrication provide a constant source of wear and breakdown and further add to the cost of the press.

It is the general object of my invention to avoid and overcome the foregoing and other difficulties and disadvantages of power presses and particularly the supports for the slides thereof by the provision of an improved three-point support for the slide during its reciprocating movement, which support insures accurate tool alignment and reduces wear, maintenance and repair.

The foregoing and other objects of my invention are achieved by the provision of a power press including in combination, a frame having spaced uprights, gibs adjustably mounted on the uprights in opposed relation, and a slide having substantially vertical ribs received between the gibs to mount the slide for reciprocating movement. The slide likewise carries a key on its

back, which key extends parallel with the ribs and is received in a keyway in the frame to thereby provide a three-point support for the slide. I preferably lubricate the bearing parts by providing reservoirs in the ribs of the slide which are connected to the bearing faces of the ribs by a plurality of passages and I lubricate the key and keyway by the provision of an oil channel in association therewith which is connected to an oil cup or reservoir.

For a better understanding of my invention reference should be had to the accompanying drawings wherein Fig. 1 is a side elevation of a power press incorporating the principles of my invention; Fig. 2 is a sectional view taken on line II—II of Fig. 1 but shown in perspective and on a larger scale to better illustrate my improved manner of mounting the slide or tool holder; Fig. 3 is a vertical cross-sectional view taken on line III—III of Fig. 2 and showing the details of oiling the key and keyway support for the slide; and Fig. 4 is a vertical cross-sectional view taken on line IV—IV of Fig. 2 and illustrating the manner of lubricating the gibbed support for the slide.

It will be understood that the principles of my invention can be employed in conjunction with reciprocating members of various kinds and as particularly employed in power presses. However, in accordance with the patent statutes I have particularly illustrated one advantageous embodiment of my invention in conjunction with an inclinable punch press which will now be described.

In Fig. 1 of the drawings, the numeral 10 indicates generally a base to which is pivotally secured as at 12 a C-shaped frame 14. The particular inclination of the frame 14 on the base 10 to best receive and discharge the work is controlled by any suitable means, as for example, the provision of an arcuate slot 16 in the base 10 which slidably receives a cap screw 18 carried by the frame 14 so that after adjusting the angle of the frame as desired the cap screw can be tightened to secure the frame rigidly to the base.

The frame 14 includes a standard work-receiving platform or bolster plate 20 to and from which a slide or tool holder 22 is reciprocated by well known crank or eccentric mechanism 24 which will not be described in detail. The slide 22 is mounted for straight line motion to and from the platform 20 in spaced flanges or uprights 26 which are usually formed integral with the frame and which terminate vertically below

the crank and eccentric mechanism 24 and vertically above the platform 28. The flanges 26 are formed with opposed inwardly directed shoulders 28 which receive vertically extending hardened metal gibs 30 which are secured in place by suitable means, such as cap screws, not shown. Cooperating with each gib 30 is another hardened metal gib 32 which is adjustably mounted for movement to and from its associated gib 30 as by the provision of cap screws 34, and which likewise can be moved in a direction parallel to the nearest face of each of the gibs 30, i. e., toward and from each other, by cap screws 36 carried in the flanges 26.

15. The slide 22 is formed with ribs 40 which extend substantially longitudinally or vertically of the slide and the ribs are preferably of the shape of a truncated isosceles triangle in horizontal cross section and, as best seen in Fig. 2, the gibs 30 and 32 are formed with inclined edges which engage in bearing relation with the outer faces of the ribs 40. A line drawn between the centers of the ribs 40 is preferably parallel to the crank shaft of the press and is in alignment with the thrust of the crank shaft and the tool carried by the slide.

20. Associated with the back of the slide 22 is a key 58 which may comprise a hardened steel key doweled or screwed to the back of the slide and extending the full length of the slide in parallel relation to the ribs 40. The key 58 is received in a keyway 52 formed in a flange or back plate 54 extending between the flanges 26 and forming a part of the frame 14 of the press. The flange or plate 54 could obviously be a separate plate bolted to the frame of the press if desired. Ordinarily the key 58 and keyway 52 are of the same length as the gibs 30-32 and the ribs 40 but I particularly contemplate increasing the length, i. e. height, of the key 58 and keyway 52 if desirable in certain presses and this can be readily done because the reciprocating mechanism 24 does not interfere.

25. Although the three-point support for the slide, as just described, comprises the most essential feature of my advance in the art, I likewise provide an efficient means for lubricating the bearing parts of my improved slide mounting. Having particular reference to Figs. 2 and 3, I form the keyway 52 with a longitudinal groove or channel 56 which terminates just short of the bottom of the plate 54 and which is connected near the upper end of the plate with an oil cup 58 by way of a passage 60. The key 58 is formed with a plurality of transverse slots 62 which insure the flow of oil to all surfaces engaging between the key and its supporting keyway.

30. With respect to the lubrication of the gibs 30 and 32 and the ribs 40, I form longitudinal or vertical recesses or bores 64 in the ribs 40 which, as shown in Fig. 4, are closed at their bottoms by plugs 66 but are connected to the bearing faces of the ribs by a plurality of substantially horizontal ducts 68. The upper ends of the bores 64 cannot carry oil cups as these would strike the slide reciprocating mechanism 24, but instead spring caps 70 are utilized to close the bores and the oil is stored in the bores and works out as

needed to the faces of the ribs by way of ducts 68, as will be understood.

35. It is believed that the operation of my improved mounting and the lubrication of the bearing parts will be evident from the foregoing description. The slide is provided with sliding support at three different points or areas which effect very accurate tool alignment and noticeably reduce wear. All bearing parts are particularly well lubricated and presses constructed as herein disclosed require materially less maintenance attention and attendant costs than do those having known types of slide support.

40. While I have particularly illustrated and described one embodiment of my invention, it should be understood that my invention is not limited thereto or thereby but is defined in the appended claims.

I claim:

1. A power press including a box-shaped frame, 20 a slide received in the box-shaped frame and including a tool carrying portion, means mounted at the upper end of the box-shaped frame for reciprocating the slide, vertically extending, triangularly shaped ribs on the opposite sides of the 25 slide and extending in opposite directions adjacent the sides of the box-shaped frame, fixed gibs on the frame engaging with the back sides of the ribs, adjustable gibs carried on the frame and engaging with the front sides of the ribs, a 30 key of rectangular cross section secured centrally to the back of the slide and in parallel relation with the ribs, the frame adjacent the key having a keyway formed therein and slidably receiving the key, said key and keyway having three 35 large flat bearing surfaces and interengaging to hold the slide against lateral or backward displacement, said slide reciprocating means and the tool carrying portion of the slide lying substantially in a common plane.

40. 2. A power press including a frame, a slide received in the frame, means for reciprocating the slide, vertically extending ribs on opposite sides of the slide, gibs on the frame engaging with the ribs, means for adjusting the gibs toward and from each other a key secured centrally to the back of the slide and in parallel relation with the ribs, the frame adjacent the key having a keyway associated therewith and slidably receiving the key, said slide ribs and said slide reciprocating means lying substantially in a common plane.

45. 3. A power press including a box-shaped frame, a slide received in the box-shaped frame and including a tool carrying portion, means mounted at the upper end of the box-shaped frame for reciprocating the slide, vertically extending ribs on the opposite sides of the slide adjacent the sides of the box-shaped frame, gibs on the frame slidably engaging with the ribs, means for adjusting the gibs toward and from each other and a key of relatively large rectangular cross section secured centrally to the back of the slide and in parallel relation with the ribs, the frame adjacent the key having a relatively large keyway associated therewith and slidably receiving the 55 key.

LOUIS E. PECK.
